UNITED STATES PATENT OFFICE.

WILLIAM F. MICHELS, OF MILWAUKEE, WISCONSIN.

DESIGN FOR A LIGHTING FIXTURE.

Application filed February 20, 1926. Serial No. 16,623. Term of patent 3½ years.

To all whom it may concern:

Be it known that I, WILLIAM F. MICHELS, a citizen of the United States, residing at Milwaukee, in the county of Milwaukee and State of Wisconsin, have invented a new, original, and ornamental Design for Lighting Fixtures, of which the following is a specification, reference being had to the accompanying drawing, forming part thereof.

Figure 1 is a fragmentary plan view of the lighting fixture, the portion indicated in dotted outline being ornamented in the same manner as the portion more fully illustrated, and

Figure 2 is a fragmentary perspective view of the lighting fixture, the portion indicated in dotted outline being ornamented in the same manner as the portion more fully illustrated.

I claim:

The ornamental design for a lighting fixture substantially as shown and described.

In testimony whereof I affix my signature at 5054 Plankinton Building, Milwaukee, Wisconsin.

WILLIAM F. MICHELS.
